UNITED STATES PATENT OFFICE.

MILLARD E. STOCKWELL, OF GRAND RAPIDS, MICHIGAN, ASSIGNOR
TO JOHN A. HODGES AND ITHIEL J. CILLEY, OF GRAND RAPIDS,
MICHIGAN.

FURNITURE.

SPECIFICATION forming part of Letters Patent No. 749,709, dated January 12, 1904.

Application filed February 16, 1903. Serial No. 143,713. (No model.)

To all whom it may concern:

Be it known that I, MILLARD E. STOCKWELL, a citizen of the United States, residing at Grand Rapids, in the county of Kent and State of Michigan, have invented certain new and useful Improvements in Furniture, of which the following is a specification.

This invention relates to improvements in metal furniture, as chairs, tables, stools, &c.; and its objects are, first, to utilize elliptical or flat tubing in the construction of the framework of this class of furniture; second, to dispense with the use of screws, bolts, &c., in assembling the framework of this class of furniture, and, third, to assemble the legs and leg-braces for metal furniture, having the metal folded and the back edges turned or curved in to avoid sharp or rough edges, without the use of screws or bolts for securing the braces. These objects are attained by the mechanism illustrated in the accompanying drawings, in which—

Figure 1 is a side elevation of a chair. Fig. 2 is a front elevation of the same. Fig. 3 is a sectional plan of the frame on line $x-x$ in Fig. 2. Fig. 4 is an elevation of a leg cut away at K to show the manner of securing the brace. Fig. 5 is a sectional plan of a leg on the line $x-x$ of Fig. 1. Fig. 6 shows a tube made of sheet metal with the back edges turned in and meeting to form a practically square edge. Fig. 7 is an elevation of a portion of a leg with the braces cut off at $y-y$ of Fig. 8 and showing the manner of assembling these parts with legs formed of sheet metal and having the back edges turned in, but not meeting, and Fig. 8 is a sectional plan of the same on the line $y-y$ of Fig. 7. Fig. 9 is a sectional side view, on the line Z Z of Fig. 10, of a leg formed of sheet metal and having the back edges rolled or curved, but not meeting, showing the manner of attaching the braces; and Fig. 10 is a sectional plan of the same on the line Z Z of Fig. 9. Fig. 11 is a back elevation of an oval or round leg made of sheet metal with the back edges meeting, with the rails cut off on the line $v-v$ of Fig. 12 and showing the manner of securing the rails; and Fig. 12 is a sectional plan of the same on the line $v-v$ of Fig.

11, showing the ends of the braces interlocked. Fig. 13 is a sectional end view of a chair-back on the line $u-u$ of Fig. 2, showing the manner of inserting the slat or spindle. Fig. 14 is a sectional perspective, and Fig. 15 is a sectional elevation, of the top of a leg on the line W W of Fig. 3, showing the manner of introducing the flanges by means of which the legs are secured to the top. Fig. 16 is a sectional side view of the back on the line $t-t$ of Fig. 13, showing a provision for preventing the back from sliding upon the slat or spindle; and Fig. 17 is a bottom plan of the same.

Similar letters refer to similar parts throughout the several views.

A represents the top or seat, as the case may be.

B represents the legs, which may be made of tubing (preferably flat or oval) or of sheet metal folded, practically, to an oval form with the back edges folded, curved, or turned in to approach each other and render the back surface smooth and convenient to handle. When made of sheet metal, the fold of the edges may be brought together to form tubes, as indicated in Figs. 6 and 11, or they may be left apart, as indicated in Figs. 7, 8, 9, and 10, so that the braces C may pass between the edges, as in Figs. 9 and 10.

In constructing the leg-frame of a piece of furniture the legs B when made of full oval or elliptical tubing are mortised, as at b, for the reception of the ends of the braces C, two of said braces entering each leg, as in Fig. 5, the lower edge being notched, as at c, so that the edge of the tubing will enter it, as in Fig. 4, and the upper edge is beveled down toward the end, as at C', so that the ends of the rails may be entered into the mortise until the notch c engages the wall of the tube without binding, and when the top of the legs B are carried toward each other, as indicated by the arrows in Fig. 4, to position for attaching them to the top A the brace will be tightly clamped between the edges of the tubes at each end of the mortises and held firmly, thus making a strong rigid brace for this portion of the frame without the use of any additional supporting elements.

When an oval tube is formed of sheet metal, as in Fig. 11, the mortise and braces should be dovetailed, as shown at *d d*, and the ends of the braces interlocked, preferably as shown 5 in Fig. 12, so that there will be no possibility of the tube spreading by reason of the strain upon the braces.

When the legs are formed of sheet metal with the back edges turned in and some distance apart, as in Figs. 8 and 10, it is advisable to pass a rivet or rivets *G* through to prevent them from spreading. When the edges are turned, practically, square in, as in Figs. 7 to 9, the ends of the braces may be 15 curved, as in Fig. 8, to hold the braces apart to position and dovetailed into the edges, as indicated in Fig. 7; but when the curved edges, as in Fig. 10, are used the ends of the braces will enter the same, as in Fig. 4, and two rivets *G'* and *G''* are inserted. These rivets serve 20 a double purpose: first, to prevent the legs from spreading at the back or open portion, and, second, to receive and support the strain of the legs upon the braces, substantially as 25 explained in connection with the description of Fig. 4.

The legs are secured to the top *A* by means of flanges *F*, preferably constructed with downwardly-projecting plugs *f*, that enter the 30 upper ends of the legs and are securely attached thereto in shape, so that they may be screwed solidly to the lower surface of the top.

In furniture requiring upwardly-projecting backs, as chairs, &c., the main posts *D* are secured to the lower side of the chair-seat well 35 forward, as indicated at *a* in Fig. 1, and are formed of a single piece of tubing, as shown in Fig. 2, and the spindles *E* are secured thereto by mortising through the main post, as at *l* in 40 Fig. 13, and passing the slats through until the upper ends, which are curved, as at *e*, bear against the upper inner surface of the tube, as shown in Figs. 13 and 16, and the danger of the tube slipping upon the slat when carrying 45 the chair thereby may be averted by spring-catches *d'*, formed from the tube at the ends of the mortises arranged to engage corresponding notches in the edges of the slats, as indicated in Figs. 16 and 17 or in any other available way. The lower ends of the slats may be 50 secured to the seat by means of screws, as at *e* in Fig. 1, and the two outside slats may be made of a single piece of metal, if desired.

Having thus fully described my invention,

what I claim as new, and desire to secure by 55 Letters Patent of the United States, is—

1. In furniture construction, a top, tubular metal legs secured thereto, each of said legs provided with a mortise at the back, braces having the ends notched upon the lower edges 60 and fitted to enter said mortises and rigidly support the legs, substantially as and for the purpose set forth.

2. In furniture construction, a top, open tubular legs secured thereto, said legs each having a mortise through the back wall, braces having the ends beveled, and notched in the lower edge, and interlocked in pairs closely fitting said mortises, substantially as and for the purpose set forth. 70

3. In furniture construction, a top, tubular legs, open at the back and the edges turned in, secured thereto, rivets passing through the tubes braces having the ends notched and fitted to enter said tubes in pairs and engage the 75 pins substantially as and for the purpose set forth.

4. In furniture construction, a top, tubular metal legs secured thereto and each of said legs provided with an opening for braces, braces 80 having notches in the lower edge near the ends and fitted to enter said openings and rigidly support the legs; with a back made of a single piece of metal tube bent and having narrow mortises through the lower wall, and slats 85 fitted snugly into said mortises and having the upper ends formed to fit the upper inner surface of the tube, the opposite ends thereof secured to the under side of the top, forming a 90 chair-back, substantially as and for the purpose set forth.

5. In furniture construction a chair having a top tubular legs secured thereto and braces supporting said legs, in combination with a tubular back post in one piece and having 95 mortises through the walls, catches formed at the end of said mortises, slats entering said mortises and having notches corresponding with the catches, the lower end of said slats secured to the chair-seat, substantially as and 100 for the purpose set forth.

Signed at Grand Rapids, Michigan, February 6, 1903.

MILLARD E. STOCKWELL.

In presence of—
ITHIEL J. CILLEY,
JOHN A. HODGES.
